(57) CLAIM

The ornamental design for the tap, as shown and described.

DESCRIPTION

FIG. 1 is a top front right perspective view of the tap mounted on a post, which post is not claimed as part of the design; FIG. 2 is a top front right perspective view of the tap shown in FIG. 1;

FIG. 3 is a bottom front right perspective view of the tap shown in FIG. 1;

FIG. 4 is a bottom front right perspective view of the tap shown in FIG. 1 from a lower angle than FIG. 3;

FIG. 5 is a top back right perspective view of the tap shown in FIG. 1;

FIG. 6 is a top plan view of the tap shown in FIG. 1;

FIG. 7 is a bottom plan view of the tap shown in FIG. 1;

FIG. 8 is a front elevation view of the tap shown in FIG. 1;

FIG. 9 is a back elevation view of the tap shown in FIG. 1; and,

FIG. 10 is a right side elevation view of the tap shown in FIG. 1, the left side elevation view being a mirror image thereof. The broken lines in FIG. 1 depict unclaimed environmental subject matter.
